UNITED STATES PATENT OFFICE.

SAM J. LUNSFORD, OF MARBLE, NORTH CAROLINA.

TRICYCLE.

1,200,379.

Specification of Letters Patent. Patented Oct. 3, 1916.

Application filed January 19, 1915. Serial No. 3,083.

To all whom it may concern:

Be it known that I, SAM J. LUNSFORD, a citizen of the United States, residing at Marble, in the county of Cherokee and State 5 of North Carolina, have invented certain new and useful Improvements in Tricycles; and I do hereby declare the following to be a full, clear, and exact description of the invention, such as will enable others skilled in 10 the art to which it appertains to make and use the same.

This invention relates to tricycles, and the primary object of the invention is to provide a motor driven tricycle which will eliminate 15 the use of manual power for propelling the tricycle.

Another object of this invention is to attach an internal combustion engine to a tricycle of ordinary type, and to connect the 20 ordinary type of hand propelling mechanism to the engine in such a manner that the operation of the hand propelling mechanism will crank the engine for starting the same.

With the foregoing and other objects in 25 view this invention consists in such novel features of construction, combination and arrangement of parts as will be hereinafter more fully described, illustrated in the accompanying drawings and claimed.

30 In describing the invention in detail reference will be had to the accompanying drawings wherein like characters designate the like or corresponding parts throughout the several views, and in which:

35 Figure 1 is a perspective view of the improved tricycle. Fig. 2 is a side elevation of the tricycle, and Fig. 3 is a top plan view of the same.

Referring more particularly to the drawings, 1 designates the tricycle as an entirety, 40 which has a rear axle 2 upon the outer ends of which are rotatably mounted traction wheels 3 and 4. The wheels 3 and 4 have pneumatic tires 5 mounted upon their periphery. The front part of the tricycle frame has a fork 6 carried thereby, which 45 rotatably supports a front wheel 7. The front wheel 7 is positioned forwardly of and substantially intermediate of the rear wheels 50 3 and 4, as is clearly shown by reference to Fig. 3 of the drawings. The tricycle supporting frame 1 has a seat 8 of the ordinary construction supported thereby and a back rest 9 positioned above and rearwardly of the seat 8. A foot rest 10 is also carried by 55 the tricycle supporting frame and positioned

forwardly and beneath the seat 8 as is ordinary in the construction of tricycles.

The tricycle supporting frame has a rod 15 secured thereto and extending forwardly 60 therefrom which rod has its outer ends enlarged as is shown at 16 to provide a bearing surface for supporting boxings or bearing blocks 17, which rotatably support a shaft 18. The ends 16 of the rod 15 are braced by 65 an arch 19 which extends transversely across the tricycle frame and has its ends secured to the upper surface of the terminals of the rod 15.

The shaft 18 has a sprocket 20 mounted 70 thereupon, about which a sprocket chain 21 travels. The sprocket chain 21 travels through a guide 22 which is carried by the arch 19, and about a sprocket 23 which is 75 positioned upwardly of the shaft 18 and is carried by a shaft 24, which is supported by a suitable bracket 26. The shaft 24 has a crank handle 25 connected thereto so as to provide for the manual rotation of the sprocket 23 for manually rotating the shaft 80 18, the purpose of which will be hereinafter more fully described.

The fork 6 has an arm 27 secured to its upper end, which arm is in turn connected to a rod 28. The rod 28 extends rearwardly 85 above the forward end of the frame and from the fork 6, and is connected to a link 29, which link is in turn connected to the lower end of an upstanding rod 30, which is provided with a handle 31 mounted upon its 90 upper end, for rotating the upstanding rod 30 for moving the fork 6 and the front wheel 7 carried thereby, for guiding the direction of travel of the tricycle.

The shaft 18 has a sprocket 35 mounted 95 thereon which has a clutch segment 36 formed upon one face thereof, which is adapted for engagement with a coöperating clutch segment 37 formed upon one side of the sprocket 20, for rotating the sprocket 35 100 and the shaft 18 synchronously with the rotation of the sprocket 20 by the hand crank 25. The sprocket 35 has a sprocket chain 38 passing thereabout, which sprocket chain also travels about a sprocket 39 which is 105 mounted upon the power shaft 40 of an ordinary internal combustion engine 41. The engine 41 is supported by suitable bracket arms 42 which are secured in any suitable manner to the frame of the tricycle 1, rearwardly of the foot rest 10 and the seat 8 and supplies the necessary power for propelling 110

the tricycle, through the connection with the shaft 18 by the sprockets 35 and 39 and the sprocket chain 38. A fuel retaining tank 43 is secured to one of the handles or arm 5 rests 44 of the tricycle outwardly thereof, by suitable metallic straps 45. The fuel retaining tank has communication with the carbureter or mixing valve through a metal tube 47, which extends across and is secured to 10 the under surface of the seat 8. The volatile fuel is fed from the carbureter or mixing valve into the combustion chamber of the engine in the ordinary manner.

The tank 43 is divided into a plurality of 15 compartments the forward end 48 of the same forming a lubricant retaining tank, to which is connected a lubricant carrying tube 49. The lubricant carrying tube 49 extends to the various parts of the internal combustion engine or motor 41 and the various other parts of the machine which need lubrication.

The standard 50 which supports the vertical rod 30 has a timer mechanism 51 mounted adjacent the upper end thereof which embodies a lever 51^a, for controlling the spark of the engine, which is furnished by batteries or other suitable mechanisms carried by a retaining box 52. The timer 51 is 25 connected to a make and break circuit mechanism 54 of the ordinary construction carried by a retaining box 52 for controlling the time of the spark of the engine.

The shaft 18 has pulleys 55 and 56 mounted thereupon adjacent its outer ends, about which pulleys travel belts 57 and 58 respectively. The belts 57 and 58 travel about rim pulleys 59 and 60 respectively, which are carried by the spokes of the rear wheels 3 and 4 of the tricycle, for rotating the wheels 3 and 4 by the action of the engine 41 for propelling the tricycle.

A pair of idlers 62 and 62^a are supported by an angled rod 63 and rest upon the belts 45 57 and 58. The idlers 62 and 62^a are provided for tensioning the belts 57 and 58 for regulating the speed of rotation of the wheels 3 and 4 thereby regulating the speed of travel of the tricycle. The angled shaft 50 63 is carried by a boxing 64, which is in turn connected to a hand lever 65 which is pivotally supported by the frame of the tricycle and extends upwardly, having its upper end positioned forwardly of the seat 8, for convenient access by a person seated upon the same. A quadrant 66 is supported by the under surface of the seat 8 and engages the lever 65 for holding the same rigidly in various adjusted positions thereby holding the idlers 62 and 62^a in adjusted 60 positions upon the belts 57 and 58 for regulating the tension of the same for loosening or tightening the friction of the belts upon the rim pulleys 59 and 60 for regulating the speed of rotation of the wheels 3 and 4.

The rear axle 2 of the tricycle has a supporting arm 67 secured thereto and extending forwardly therefrom, to the forward end of which is pivotally connected a lever 68. The lever 68 has a hand grip 69 formed upon its upper end, and a link 70 pivotally connected to its lower end, which is positioned beneath the pivotal point 71 of the lever and the bracket 67. The link 70 is connected to a friction brake band 72 which passes about a friction brake pulley 73 carried by the rear axle, and is secured in any suitable manner to the upper surface of the bracket arm 67 as is shown at 74, so that when the lever 69 is oscillated, the brake band 72 will be tightened or loosened upon the friction brake drum 73 for facilitating or retarding the travel of the tricycle, depending upon the direction in which the lever 68 is moved. The arm or bracket 15 is supported by suitable bracing arms 76, which extend forwardly from the supporting structure of the tricycle and are secured to the boxing 17 for steadyng the movement of the shaft 18.

A muffler 77 of ordinary construction is connected to the end of the exhaust pipe 78 of the motor or engine 41 and is provided for decreasing the sound of exhaust of the engine. When it is desired to operate the 95 improved motor driven tricycle, the spark regulating mechanism 51 is properly set for permitting of the sparking of the engine, and the shaft 18 is manually rotated through the rotation of the sprocket 23 by the crank handle 25. This cranks or starts the engine or motor 41, and provides for initiative movement thereof until the proper gas has been administered to the combustion chamber and exploded therein, for operating the 105 engine upon its own power. The engine will transmit its power to the shaft 18 through the medium of the sprockets 35, 39 and the sprocket chain 38, in the manner heretofore described. The power of the motor or engine will in turn be imparted to the rear wheels 3 and 4 of the tricycle by means of the pulleys 55, 56, the rim pulleys 59 and 60 and the belts 57 and 58, providing means for propelling the tricycle. The speed of 110 travel of the tricycle is regulated by the adjusting of the idler 62 for regulating the tension of the belt as it passes about the rim pulley 60, and by operating the brake lever 68 the travel of the tricycle may be retarded 115 or completely stopped if it is so desired.

From the foregoing description taken in connection with the accompanying drawings the advantages of construction and of the method of operation of the improved tricycle will be readily apparent to those skilled in the art to which this invention appertains and, while in the foregoing description, the principle of the operation of this invention has been described together with various 120 125 130

features of construction, it is to be understood that certain minor features of construction, combination and arrangement of parts may be altered to suit practical conditions provided such alterations are comprehended within the scope of what is claimed.

What is claimed is:—

1. The combination with an ordinary tricycle, embodying a front wheel, rear wheel, and an axle, of an ordinary internal combustion engine supported by said tricycle, a shaft extending transversely across said tricycle and carried forwardly of said rear wheels, means for operatively connecting said shaft to said internal combustion engine for rotating said shaft by the operation of said engine, means for imparting initiative rotation to said shaft for cranking said engine, rim pulleys carried by said rear wheels, pulleys carried by said shaft, belts passing about said pulleys and said rim pulleys for transmitting the rotation of said shaft to said rear wheels, and means for regulating the tension of said belts upon said rim pulleys for regulating the speed of rotation thereof.
2. The combination with an ordinary tricycle, embodying a front wheel, a supporting frame, rear wheels, and a seat structure, and of an ordinary internal combustion engine carried by said supporting structure, a shaft rotatably supported forwardly of said engine, means for imparting rotation to said shaft upon the operation of said motor,

spark controlling means for controlling the 35 sparking of said engine, pulleys mounted upon said shaft, rim pulleys carried by said rear wheels, belts traveling about said pulleys and said rim pulleys for imparting the rotation of said shaft to said rear wheels for 40 propelling tricycle, an idler resting upon one of said belts, and means for regulating the pressure of said idler upon said belt for regulating the tension of the belt for controlling the speed of travel of the rear 45 wheels.

3. The combination with an ordinary tricycle, embodying a front wheel and rear wheels, of an ordinary internal combustion engine supported by said tricycle, a shaft 50 rotatably carried by said tricycle forwardly of the rear axle thereof, and operatively connected to said internal combustion engine and the rear wheels of said tricycle for imparting rotation thereto, means for manually imparting an initiative rotation to said shaft for cranking said engine, said means including a sprocket mounted on said shaft, a second sprocket secured to said tricycle above said first mentioned sprocket, and a 55 crank handle secured to said second mentioned sprocket for manual rotation thereof.

In testimony whereof I affix my signature in presence of two witnesses.

SAM J. LUNSFORD.
